United States Patent Office

Des. 208,320

Patented Aug. 15, 1967

208,320

DISPENSER FOR GRANULATED MATERIAL OR THE LIKE

Fred Stark, Niles, Ill., assignor to Mid-America Iron and
Steel Corp., Chicago, Ill., a corporation of Illinois

Filed Dec. 20, 1965, Ser. No. 244

Term of patent 14 years

(Cl. D44—22)

FIG. 1 is a perspective view of a dispenser for granulated material or the like showing my new design;
FIG. 2 is a side elevational view thereof;
FIG. 3 is a front elevational view thereof;
FIG. 4 is a rear elevational view;
FIG. 5 is a top plan view; and
FIG. 6 is a bottom plan view.

I claim:

The ornamental design for a dispenser for granulated material or the like, as shown.
